(57) **CLAIM**

The ornamental design for a medical dressing, as shown and described.

DESCRIPTION

The file of this patent contains at least one drawing executed in color. Copies of this patent with color drawing(s)/photograph(s) will be provided by the Office upon request and payment of the necessary fee.

FIG. 1 is a perspective view of a first embodiment of a medical dressing showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof;

FIG. 8 is a perspective view of a second embodiment of a medical dressing showing our new design;

FIG. 9 is a top plan view thereof;

FIG. 10 is a bottom plan view thereof;

FIG. 11 is a right side elevational view thereof;

FIG. 12 is a left side elevational view thereof;

FIG. 13 is a front elevational view thereof;

FIG. 14 is a rear elevational view thereof;

FIG. 15 is a perspective view of a third embodiment of a medical dressing showing our new design;

FIG. 16 is a top plan view thereof;

FIG. 17 is a bottom plan view thereof;

FIG. 18 is a right side elevational view thereof;

FIG. 19 is a left side elevational view thereof;

FIG. 20 is a front elevational view thereof; and,

FIG. 21 is a rear elevational view thereof.

In the drawings, same sized broken lines of the medical dressing form portions of the claimed design.

In the drawings, the shaded areas shown in FIGS. 8, 9, 15, and 16 form portions of the claimed design.

In the drawings, color forms part of the claimed design for the third embodiment of the medical dressing, shown in

(Continued)

FIGS. 15-21. Color does not form part of the claimed design (56)
for the embodiments shown in FIGS. 1-14.
